(57) **CLAIM**

The ornamental design for a cushion material, as shown and described.

DESCRIPTION

FIG. 1 is a front view of a cushion material of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is an enlarged view thereof defined by the line 7-7 and 701-701 in FIG. 3;

FIG. 8 is an enlarged sectional view thereof taken along the line 8-8 in FIG. 7;

FIG. 9 is an enlarged sectional view thereof taken along the line 9-9 in FIG. 7;

FIG. 10 is an enlarged sectional view thereof taken along the line 10-10 in FIG. 7;

FIG. 11 is an enlarged sectional view thereof taken along the line 11-11 in FIG. 7; and,

FIG. 12 is an enlarged perspective view thereof defined by the line 1201-1201 and 1202-1202 from the direction 12 in FIG. 7.

The broken lines show portions of a cushion material that form no part of the claimed design.

The alternate long and short dash lines are the boundary lines between the claimed parts and the non-claimed parts or indicator arrow lines and form no part of the claimed design.
